US00D618349S

(12) **United States Design Patent**
Krishna et al.

(10) **Patent No.:** **US D618,349 S**
(45) **Date of Patent:** **** Jun. 22, 2010**

(54) **SPINAL STABILIZATION DEVICE**

(75) Inventors: **Manoj Krishna**, Yarm (GB); **Tai Friesem**, Ingleby Barwick (GB); **Steven Brown**, Parkland, FL (US); **Jose Fernandez**, Coral Springs, FL (US)

(73) Assignee: **Disc Motion Technologies, Inc.**, Boca Raton, FL (US)

(**) Term: **14 Years**

(21) Appl. No.: **29/326,552**

(22) Filed: **Oct. 20, 2008**

Related U.S. Application Data

(63) Continuation-in-part of application No. 12/103,576, filed on Apr. 15, 2008, which is a continuation-in-part of application No. 11/728,204, filed on Mar. 23, 2007.

(51) **LOC (9) Cl.** **24-03**

CLAIM

The ornamental design for a spinal stabilization device, as shown.

DESCRIPTION

FIG. 1 is a perspective view of a spinal stabilization device showing our new design;

FIG. 2 is a first side view thereof;

FIG. 3 is a second side view thereof;

FIG. 4 is a front view thereof;

FIG. 5 is a rear view thereof;

FIG. 6 is a first end view thereof; and,

FIG. 7 is a second end view thereof.
